UNITED STATES PATENT OFFICE.

ALAN K. GILLESPIE, OF ST. LOUIS, MISSOURI, ASSIGNOR TO BRECHT COMPANY, OF ST. LOUIS, MISSOURI, A CORPORATION OF MISSOURI.

REFRIGERATOR.

1,252,565.

Specification of Letters Patent.

Patented Jan. 8, 1918.

Application filed October 26, 1916. Serial No. 127,754.

To all whom it may concern:

Be it known that I, ALAN K. GILLESPIE, a citizen of the United States of America, residing at the city of St. Louis, State of Missouri, United States of America, have invented a certain new and useful Refrigerator, of which the following is such a full, clear, and exact description as will enable any one skilled in the art to which it applies to make and use the same, reference being had to the accompanying drawings, forming part of this specification.

My invention relates to an improvement in counter refrigerators, and its objects are to provide an arrangement in which the refrigerating means is situated below a display chamber in connection with means for maintaining a suitably low temperature throughout the display chamber; to provide an efficient and novel form of ice chamber; and to so arrange all the parts as to form a refrigerator having storage and display chambers in which the display chamber will be of convenient height and easy of access. Other objects and advantages of my invention will appear from the following more detailed description.

In the accompanying drawings, Figure 1 is a front elevational view of a refrigerator constructed in accordance with my invention; Fig. 2 is a view partly in plan and partly in horizontal section along line 2—2' of Fig. 1; Fig. 3 is a vertical transverse cross section along line 3—3' of Fig. 1; and Fig. 4 is a perspective view of the ice chamber.

The refrigerator is provided with the usual suitably insulated walls, and comprises a display chamber 1, a storage chamber 2 and ice chambers 3, spaced apart and situated between the display chamber and the storage chamber. The ice chambers communicate with a common ice hopper 4, closed by a plurality of doors 5. This hopper is provided with an inclined interior surface 6, as shown in Fig. 3, which facilitates the forcing of ice from the hopper into the ice chambers 3.

The display chamber is provided with doors 7, partly of glass, and the front wall of this chamber is formed of a plurality of spaced glass plates 8.

The ice chambers 3 terminate short of the front wall of the refrigerator, and an insulating member 9 passing lengthwise of

the refrigerator and across the ends of the ice chambers forms, with the front wall of the refrigerator, an air passage 10, connecting the storage chamber 2 with the display chamber 1. A glass baffle plate 11 extends 60 lengthwise of the display chamber and from the insulating member 9 to a point near the top of the chamber and forms, with the front wall 8, a continuation of the air passage 10.

65

A drain pipe or pipes 12 are provided for the ice chambers and are placed in any suitable position. Articles to be kept cool are placed in the storage chamber 2 through a door 13, or if they are to be displayed, into 70 the chamber 1 through a door 7.

In the operation of the refrigerator the air is brought to its lowest temperature while between and adjacent to the ice chambers 3. The warmest air will of course be 75 that adjacent to the walls of the chambers, and particularly in the passage 10. The condition just described leads to the circulation of air from the display chamber downward between the various ice chambers and 80 upward to the display chamber through the passage 10. This circulation will be continuously maintained, because the temperature of the air is always reduced, while passing between the ice chambers 3, to a 85 point below that of the air in other parts of the chamber, and this heavier air moves downwardly, displacing and forcing through the passage 10 the lighter air underneath it.

It will be noted that with the form of 90 ice chambers I employ, a very large area of the cooling surface is presented to the air with the result that I may use a smaller quantity of salt in the ice chambers, or I can reduce the temperature in the refrigerator to a point lower than would be possible if a smaller area of cooling surface were provided. The spacing of the ice chambers throughout the length of the refrigerator coöperating with the baffle 11, 95 100 also results in an even distribution of cooled air throughout all parts of the display chamber.

Having fully described my invention, what I claim as new and desire to secure by 105 Letters Patent of the United States is:

1. A refrigerator comprising an upper display chamber, a plurality of containers for cooling means located beneath said chamber and spaced apart to provide a plu- 110

rality of flues for the egress of air from the display chamber.

2. A refrigerator comprising an upper display chamber, a lower chamber, a plurality of containers for cooling means located beneath said upper chamber and spaced apart to provide a plurality of flues for the downward passage of air from the upper to the lower chamber, and a flue for the upward passage of air from the lower to the upper chamber.

3. A refrigerator comprising a lower storage chamber, an upper display chamber, a plurality of inclosed ice containers between said chambers and spaced apart to provide a plurality of passages between them from the upper to the lower chamber, and means forming a passage for the return of air from the lower to the upper chamber, said means comprising a baffle extending to the upper part of the display chamber.

4. A refrigerator comprising an upper display chamber having a transparent front wall, a lower storage chamber, containers for cooling means located between said chambers and spaced apart to provide pas-

sages for connecting the upper and lower chambers, means forming a passage for the upward movement of air from the lower to the upper chamber, said means comprising a transparent baffle located adjacent to the transparent wall of the upper chamber and extending to the upper part of said chamber.

5. In a refrigerator, the combination of a refrigerating chamber, and containers for cooling means arranged to provide a plurality of air passages adjacent to the containers, said air passages communicating with the refrigerating chamber and spaced over one wall of said chamber.

6. In a counter refrigerator, the combination of an upper display chamber, a lower storage chamber, a plurality of inclosed ice containers located between said chambers and spaced apart, said containers extending to a point back of the display chamber, and an ice hopper communicating with the rear portions of said chambers.

In testimony whereof, I have hereunto set my hand and affixed my seal.

ALAN K. GILLESPIE. [L.S.]
